J. VAUGHAN MERRICK AND W. H. MERRICK, OF PHILADELPHIA,
PENNSYLVANIA.

Letters Patent No. 94,429, dated August 31, 1869.

IMPROVED HOISTING-APPARATUS.

The Schedule referred to in these Letters Patent and making part of the same.

To all whom it may concern:

Be it known that we, J. VAUGHAN MERRICK and WILLIAM H. MERRICK, both of Philadelphia, Pennsylvania, have invented certain Improvements in Hoisting-Apparatus; and we do hereby declare the following to be a full, clear, and exact description of the same.

Our invention relates to an improvement on, or addition to the hoisting-apparatus for which Letters Patent were granted to us on the 9th day of June, 1868, and our present invention, which is applicable to inclined planes having two tracks, and to duplex hoisting-apparatus having two cages, consists in causing one car or cage, by the mechanism hereinafter described, or any equivalent to the same, to arrest the other car or cage, should the hoisting-rope of the latter break.

In order to enable others skilled in the art to make and use our invention we will now proceed to describe its construction and operation, reference being had to the accompanying drawing, which forms a part of this specification, and in which—

Figure 1 is a vertical section of an inclined plane, having two tracks, and showing our invention;

Figure 2, a view of the inclined plane and cars, looking in the direction of the arrow;

Figure 3, an end view of one of the cars, drawn to an enlarged scale;

Figure 4, a vertical section on the line 1-2, fig. 3;

Figure 5, a plan view of the operating-mechanism attached to the car; and

Figures 6 and 7, diagrams, illustrating modifications of our invention.

Similar letters refer to similar parts throughout the several views.

Although we have selected, for illustrating our invention, an inclined plane, with double track, for hoisting one car or series of cars, while another is being lowered, it should be distinctly understood in the outset, that our invention is not limited to inclined planes, but may be applied to all duplex hoisting-apparatus, whether inclined or vertical.

A and A' are the rails of one track of the inclined plane, and B and B' the rails of the adjacent track, these rails being adapted to the flanged wheels of the cars D and D'.

A continuous rack, E, with teeth on both sides, is secured to the track between the rails, or, as will be explained hereafter, two racks may be secured to the track, so that the guiding-pulleys for the hoisting-rope may be arranged between them.

To the front of each car is secured a substantial frame, F, carrying two vertical spindles G G, to each of which is secured a lever, H, as well as an arm, I, which is furnished with teeth, adapted to those on the

rack E, these two arms forming jaws, which, when operated in the manner described hereafter, serve to grip the rack, and arrest the car to which the above-described mechanism is attached.

To the long arms d d of the lever H, is connected the hoisting-rope J, in the manner illustrated in fig. 5, and to the short arms of the same levers of one car, D, on one track, is connected the rope or chain K, which passes round the guide-pulleys e e at the head of the inclined plane, and is secured to the short arms of similar levers of the car on the other track.

It has not been deemed necessary to illustrate any specific hoisting-gear, as this may be varied without in any way affecting our invention.

Should the hoisting-rope of one or the other of the cars break, that of the car D, for instance, the control of the levers H H of that car by the rope ceases, and the levers are at once under the control of the rope K and car D', and the tendency of the latter to descend the inclined plane, causes the toothed arms I to move from the position shown in black lines, fig. 5, where they are clear of the rack E, to that shown in red lines, where the teeth of the said arms fit those of the rack, and the car D will be at once arrested.

In like manner, should the hoisting-rope of the car D' be broken, the car D will act as a counterbalance to prevent, through the medium of the mechanism described, the descent of the said car D'.

It will be seen that our present invention is closely allied to that for which Letters Patent were granted to us on the 9th day of June, 1868. In that patent, however, a counterweight was used for operating the devices for arresting a cage, should the hoisting-rope break, whereas, in our present invention, one car or set of cars, on one track, is in reality the counterweight for the other car or cars on the other track, or in other words, the car or cars of one track are caused to arrest those on the other track, should the hoisting-rope of the latter cars break. It will be evident that (as before remarked) our present invention may be applied to vertical hoisting-apparatus, on which two cages are used, one ascending while the other is descending, the arresting-mechanism of one cage being connected to that of the other cage, in the manner described above.

In many instances, the guiding-pulleys for the hoisting-ropes, used on inclined planes, would not permit the placing of the double rack midway between the opposite rails of the track. In such cases, where two hoisting-ropes for each track, one on each side, would be impracticable, two single racks, E E, one on each side of the guide-pulley, for the hoisting-rope, may be used, as shown in the modification, fig. 6, which will be readily understood without description. If desired, independent racks may be dispensed with, and

teeth may be formed on the rails themselves, the arresting-mechanism being modified accordingly, or the racks, although to be preferred as determined means of arresting the cars when the rope breaks, may be dispensed with, and levers, with cam-like short arms, instead of toothed arms, may be made to grip a smooth bar or rail, as shown in fig. 7; in fact, the arresting-mechanism may be altered and modified in many respects, without departing from the main features of our invention.

We therefore claim, and desire to secure by Letters Patent—

Duplex hoisting-apparatus, inclined or vertical, in

which one car or hoisting-cage is caused, by the mechanism herein described, or any equivalent to the same, to arrest the other car or cage, should the hoisting-rope of the latter break, all substantially as herein set forth.

In testimony whereof, we have signed our names to this specification, in the presence of two subscribing witnesses.

J. VAUGHAN MERRICK.
W. H. MERRICK.
